OF D 16,071

EX

DESIGN.

—
A. EUSTON.

SAMPLE SHOT CASE.

No. 16,071.

Patented May 5, 1885.

UNITED STATES PATENT OFFICE.

ALEXANDER EUSTON, OF ST. LOUIS, MISSOURI.

DESIGN FOR A SAMPLE-SHOT CASE.

SPECIFICATION forming part of Design No. 16,071, dated May 5, 1885.

Application filed March 30, 1885. Term of patent 14 years.

To all whom it may concern:

Be it known that I, ALEXANDER EUSTON, of the city of St. Louis, in the State of Missouri, have invented and produced a Design 5 for Sample-Shot Cases, of which the following is a full, clear, and exact description, reference being had to the accompanying drawing, forming part of this specification, and which is an elevation of my newly-designed case. 10 My invention relates to a show-case; and my design consists of a conventional representation of a shot-tower, as shown in the drawing. Referring to the drawing, A represents the

base of the tower or case, B the trunk, and 15 C the top or crown, the whole being designed to represent a conventional tower constructed for the manufacture of shot.

I claim as my invention—

The design for a sample-shot case, consisting 20 of a conventional representation of a shot-tower having the base A, body B, and top C, as shown and described.

ALEX. EUSTON.
